DUAL BREADING BOWL

Rose A. Davis, Washington, D. C.

Application October 6, 1955, Serial No. 38,245

Term of patent 14 years

(Cl. D44—1)

Fig. 1

Fig. 2

Fig. 3

Fig. 1 is a bottom plan view of a dual breading bowl showing my new design;

Fig. 2 is a top plan view thereof.

Fig. 3 is a longitudinal, central vertical section through Fig. 2.

I claim:

The ornamental design for a dual breading bowl, substantially as shown.
